VEHICLE SIGNAL

Filed Nov. 29, 1929

Edward E. Rich

INVENTOR

BY Victor J. Evans

ATTORNEY

UNITED STATES PATENT OFFICE

EDWARD EMIL RICH, OF CHICAGO, ILLINOIS

DESIGN FOR A VEHICLE SIGNAL

Application filed November 29, 1929. Serial No. 33,584. Term of patent 14 years.

To all whom it may concern:

Be it known that I, EDWARD EMIL RICH, a citizen of the United States of America, residing at Chicago, in the county of Cook and State of Illinois, have invented a new, original, and ornamental Design for a Vehicle Signal, of which the following is a specification, reference being had to the accompanying drawing, which forms a part thereof.

In the drawing the figure shown is a perspective view of the invention.

I claim:

The ornamental design for a vehicle signal, as shown.

EDWARD E. RICH.
